BRAKE

Albert Cooper Starr, Nephi, Utah, assignor to
Bendix Brake Company, South Bend, Ind., a
corporation of Illinois

Application July 19, 1928. Serial No. 293,872

24 Claims. (Cl. 188—78)

This invention relates to brakes, and is illustrated as embodied in an internal expanding automobile brake. An object of the invention is to provide a simple and powerful brake which can be made economically on a large scale.

One feature of the invention relates to the arrangement of a novel brake-applying lever having thrust portions on its opposite sides, and which preferably is pivoted to another operating lever in a manner permitting it to float to balance its thrusts in opposite directions, and which in the preferred embodiment is arranged in an inclined position in operative engagement with thrust projections on the ends of the brake shoes or their equivalents.

Another important feature relates to a novel linkage or lever mechanism for forcing the secondary shoe or equivalent friction means against the drum when the brake is applied, and which preferably includes a stop which determines the released position of the shoe.

The above and other objects and features of the invention, including various novel details of construction, will be apparent from the following description of the illustrative embodiment shown in the accompanying drawing, in which:

Figure 1 is a vertical section through the brake just inside the head of the brake drum, and showing the brake shoes in side elevation.

Figs. 2, 3, and 4 are respectively sections on lines 2—2, 3—3, and 4—4 on Fig. 1.

The brake selected for illustration includes a rotatable drum 10, at the open side of which is a support such as a backing plate 12. Within the drum is arranged the friction means, preferably including a primary shoe 14, a secondary shoe 16, and an auxiliary shoe 18. Shoe 14 is connected to shoe 16 by a floating pivot 20, and shoe 18 is anchored on a fixed pivot 22 carried by the backing plate. Shoe 16 preferably projects past the pivot 22 nearly to the heel of the friction surface of shoe 18, thus in effect overlapping a portion of the shoe 18.

The brake is preferably applied by a novel floating lever 24, having a thrust projection 26 on its right side at one end, and having another thrust projection 28 on its left side between its ends. Thrust portions 26 and 28 engage respectively two projections 30 and 32, on shoes 18 and 14, to force the shoes apart, against the resistance of a return spring 34, to apply the brake. Projections 30 and 32 preferably terminate approximately at the same (vertical) radius of the drum, lever 24 being inclined between them at an angle 55 to the vertical drum radius, so that the thrusts

from portions 26 and 28 are, for the short arcs of movement, substantially perpendicular to the ends of projections 30 and 32, and there is substantially no rubbing or friction of portions 26 and 28 against the projections 30 and 32.

Lever 24 is preferably connected, by a pivot 36 or the like, to an operating lever 38 having a fixed fulcrum, and which is shown keyed on the brake-applying shaft 40.

Shoe 16 is shown formed with a slot 42 embracing a pin or roller 44 projecting laterally from a member 46 mounted on a pivot 48 carried by the backing plate, and rocked about pivot 48 as an operating lever by movement of shoe 16 to the right when the brake is applied. A device 50 is pivoted, preferably on member 46, by a pin 52, and has a pin or roller 54 engaging the edge of the stiffening web of shoe 16. Movement of member 46 to the right causes the end of device 50 to be held by a fixed adjustable stop 56, to rock pin 54 downwardly to force the shoe 16 toward the drum.

When the brake is released, auxiliary return springs 58 and 60, connected to opposite ends of shoe 16, urge the shoe inwardly against a cam 80 surface on the bottom of the stop 56.

While one illustrative embodiment has been described in detail, it is not my intention to limit its scope to that particular embodiment, or otherwise than by the terms of the appended claims.

I claim:

1. A brake comprising, in combination, a drum, friction members within the drum having adjacent separable ends formed with projections one of which is further from the center of the drum than the other and which terminate approximately at the same radius of the drum, and an operating lever inclined with respect to said radius and extending between said separable ends and having thrust portions engaging said projections, together with operating means engaging the end of said lever inside of said ends.

2. A brake comprising, in combination, a drum, friction members within the drum having adjacent separable ends formed with projections one of which is further from the center of the drum than the other and which terminate approximately at the same radius of the drum, and a floating operating lever extending between said separable ends and having thrust portions engaging said projections, together with operating means engaging the end of said lever inside of said ends.

3. A brake comprising, in combination, a drum, friction members within the drum having adjacent separable ends formed with projections one

- of which is further from the center of the drum than the other and which terminate approximately at the same radius of the drum, and a floating operating lever extending between said separable 5 ends and having thrust portions engaging said projections, together with another lever having a fixed fulcrum and pivotally connected to the end of said floating operating lever.
4. A brake-applying lever having a pivot at one 10 end and formed with a thrust projection at one side of the lever at the other end and with a thrust projection on the other side of the lever between its ends.
5. A brake-applying lever formed with a thrust 15 projection at one side of the lever at one end and with a thrust projection on the other side of the lever between its ends.
6. A brake comprising, in combination, a drum, 20 a pair of connected shoes arranged end to end and engageable with the drum, applying means acting on one shoe directly and indirectly on the other shoe through said one shoe, and connected power-multiplying levers acting on said other shoe, and forcing it radially against the drum automatically when the brake is applied.
7. A brake comprising, in combination, a drum, 25 a pair of connected shoes arranged end to end and engageable with the drum, applying means acting on one shoe directly and indirectly on the other shoe through said one shoe, a link connected to said other shoe, and means operated by the swinging of the link to force said other shoe against the drum automatically when the brake is applied.
8. A brake comprising, in combination, a drum, 30 friction means adjacent the drum, a member pivoted at one end and operatively engaged by the friction means at its other end, and a device pivoted on said member and operated by movement of said member to force the friction means toward the drum.
9. A brake comprising, in combination, a drum, 35 friction means adjacent the drum, a member pivoted at one end and operatively engaged by the friction means at its other end, and a pivotally-mounted device operated by movement of said member to force the friction means toward the drum.
10. A brake comprising, in combination, a drum, 40 friction means engageable with the drum, a member engaged by the friction means and moved by the application of the brake, a device engaging the friction means and pivotally engaged by said member, and a stop engaged by said device and operating when said member moves to rock said device to force the friction means toward the drum.
11. A brake comprising, in combination, a drum, 45 friction means engageable with the drum, a member engaged by the friction means and moved by the application of the brake, a device engaging the friction means and pivotally engaged by said member, a stop engaged by said device and operating when said member moves to rock said device to force the friction means toward the drum, said stop also being engaged by the friction means to determine its position when the brake is released.
12. A brake comprising, in combination, a drum, 50 a pair of connected shoes arranged end to end and engageable with the drum, applying means acting on one shoe directly and indirectly on the other shoe through said one shoe, and connected power-multiplying levers acting on said other shoe, and forcing it against the drum automatically when the brake is applied, together with a third shoe which is anchored and which is operatively engaged by said applying means.
13. A brake comprising, in combination, a drum, 55 a pair of connected shoes arranged end to end and engageable with the drum, applying means acting on one shoe directly and indirectly on the other shoe through said one shoe, and connected power-multiplying levers acting on said other shoe, and forcing it against the drum automatically when the brake is applied, together with a third shoe which is operatively engaged by said applying means.
14. A brake comprising a drum, in combination 60 with friction means within the drum, a fixed pivot adapted to serve as an anchor taking the torque of the friction means, and a leverage device mounted on said pivot and having a pivotal and radially-slidable connection with the friction means and having a part pivoted thereto and operated by the friction means swinging said device on the pivot in such a manner as to force the friction means slidably of said connection radially against the drum.
15. A brake comprising a drum, in combination 65 with friction means within the drum, means adapted to serve as an anchor taking the torque of the friction means, and a device pivoted on said means and having a pivotal and radially-slidable connection with the friction means and having a part movably connected therewith and operated by movement of the friction means in such a manner as to force the friction means slidably of said connection radially against the drum.
16. A brake comprising a drum, in combination 70 with friction means within the drum, means adapted to serve as an anchor taking the torque of the friction means, and a device pivoted on said means and having a pivotal and radially-slidable connection with the friction means and having connected relatively-movable parts one of which is operated by movement of the friction means in such a manner as to force the friction means slidably of said connection radially against the drum, the torque of the friction means being transmitted to the anchor means through said device.
17. A brake comprising a drum, in combination 75 with friction means, and a pivotally-mounted device connected to the friction means and taking its torque and having connected relatively-movable parts one of which is operated by pivotal movement of the device to force the friction means against the drum.
18. A brake comprising a drum, in combination 80 with friction means, and a pivotally-movable anchor device taking the torque of the friction means and including pivotally connected parts arranged to be moved by the friction means to force the friction means adjacent the anchor device against the drum.
19. A brake comprising a drum, in combination 85 with friction means, and a pivotally-movable anchor device taking the torque of the friction means and arranged to be moved by the friction means to force the friction means adjacent the anchor device against the drum, said pivotally-movable device having a projection and the friction means having a part slidably embracing the projection in a manner permitting the described shifting of the friction means toward the drum, together with a lever pivotally engaging said device and the friction means and arranged to move the friction means as described.
20. A brake comprising a drum, in combination 90 with friction means, and a pivotally-movable anchor device taking the torque of the friction means and including pivotally connected parts arranged to be moved by the friction means to force the friction means adjacent the anchor device against the drum.
21. A brake comprising a drum, in combination 95 with friction means, and a pivotally-movable anchor device taking the torque of the friction means and including pivotally connected parts arranged to be moved by the friction means to force the friction means adjacent the anchor device against the drum.
22. A brake comprising a drum, in combination 100 with friction means, and a pivotally-movable anchor device taking the torque of the friction means and including pivotally connected parts arranged to be moved by the friction means to force the friction means adjacent the anchor device against the drum.
23. A brake comprising a drum, in combination 105 with friction means, and a pivotally-movable anchor device taking the torque of the friction means and including pivotally connected parts arranged to be moved by the friction means to force the friction means adjacent the anchor device against the drum.
24. A brake comprising a drum, in combination 110 with friction means, and a pivotally-movable anchor device taking the torque of the friction means and including pivotally connected parts arranged to be moved by the friction means to force the friction means adjacent the anchor device against the drum.
25. A brake comprising a drum, in combination 115 with friction means, and a pivotally-movable anchor device taking the torque of the friction means and including pivotally connected parts arranged to be moved by the friction means to force the friction means adjacent the anchor device against the drum.
26. A brake comprising a drum, in combination 120 with friction means, and a pivotally-movable anchor device taking the torque of the friction means and including pivotally connected parts arranged to be moved by the friction means to force the friction means adjacent the anchor device against the drum.
27. A brake comprising a drum, in combination 125 with friction means, and a pivotally-movable anchor device taking the torque of the friction means and including pivotally connected parts arranged to be moved by the friction means to force the friction means adjacent the anchor device against the drum.
28. A brake comprising a drum, in combination 130 with friction means, and a pivotally-movable anchor device taking the torque of the friction means and including pivotally connected parts arranged to be moved by the friction means to force the friction means adjacent the anchor device against the drum.
29. A brake comprising a drum, in combination 135 with friction means, and a pivotally-movable anchor device taking the torque of the friction means and including pivotally connected parts arranged to be moved by the friction means to force the friction means adjacent the anchor device against the drum.
30. A brake comprising a drum, in combination 140 with friction means, and a pivotally-movable anchor device taking the torque of the friction means and including pivotally connected parts arranged to be moved by the friction means to force the friction means adjacent the anchor device against the drum.
31. A brake comprising a drum, in combination 145 with friction means, and a pivotally-movable anchor device taking the torque of the friction means and including pivotally connected parts arranged to be moved by the friction means to force the friction means adjacent the anchor device against the drum.
32. A brake comprising a drum, in combination 150 with friction means, and a pivotally-movable anchor device taking the torque of the friction means and including pivotally connected parts arranged to be moved by the friction means to force the friction means adjacent the anchor device against the drum.

- tion with friction means, and a pivotally-movable anchor device taking the torque of the friction means and having a part arranged to be moved by the friction means to force the friction means adjacent the anchor device against the drum, said part being pivotally carried by said device. 5 for the friction means at one side of the drum and provided, across the drum from the applying device, with anchorage means including an anchor pivot and a lever device mounted on said pivot and provided with a pivotally-mounted part actuated by movement of the friction means when the brake is applied to shift the adjacent portion of the friction means toward the drum. 80
21. A brake friction means anchorage device comprising a lever mounted on a fixed anchor pivot and having pivotal and radially-slidable engagement with the friction means, and a second lever pivoted to an intermediate part of the first lever. 10 24. A brake comprising a drum and friction means within the drum and an applying device for the friction means at one side of the drum and provided, across the drum from the applying device, with anchorage means including an anchor pivot and a lever device mounted on said pivot and transmitting the braking torque of the friction means thereto and provided with a pivotally-mounted part actuated by movement of the friction means when the brake is applied to shift the adjacent portion of the friction means toward the drum. 85
22. A brake friction means anchorage device comprising a lever mounted on a fixed anchor pivot and having pivotal and radially-slidable engagement with the friction means and having a relatively-movable part shifted with respect to said lever by movement of the brake friction means in such a manner as to force the friction means toward the drum. 15 90
23. A brake comprising a drum and friction means within the drum and an applying device 20 95
